(57) **CLAIM**

I claim the ornamental design for scissor handles, as shown and described.

DESCRIPTION

FIG. 1 is a perspective view of scissor handles showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view along line 8-8 of FIG. 2; and,

FIG. 9 is a cross-sectional view along line 9-9 of FIG. 2.

The ornamental design which is claimed is shown in solid lines in the drawings. The broken lines in the drawings are for illustrative purposes only and form no part of the claimed design.
